UNITED STATES PATENT OFFICE.

ABRAHAM T. WELCH, OF BALTIMORE, MARYLAND.

CENTRIFUGAL MACHINE.

SPECIFICATION forming part of Letters Patent No. 636,016, dated October 31, 1899.

Application filed January 21, 1899. Serial No. 702,905. (No model.)

To all whom it may concern:

Be it known that I, ABRAHAM T. WELCH, a citizen of the United States, residing at Baltimore, in the State of Maryland, have invented 5 certain new and useful Improvements in Centrifugal Machines for Separating Water from Matter, of which the following is a specification.

This invention relates to a centrifugal machine to be employed instead of a press for separating water from animal matter, cooked fish, garbage, and the like.

This invention is designed for separating water from various kinds of matter, and particularly those kinds of matter wherein the proportion of moisture in different parts of the bulk varies considerably.

In a large bulk of matter, such as fish scrap, which is usually piled up, the variation in proportions of moisture from the top of the pile to the bottom is very great, the moisture draining from the top to the bottom, where it is greatest. It will therefore be seen that if matter from such a pile is fed into 25 the machine and allowed to pass through without regulating or controlling the discharge different parts of the discharged matter would still vary in the proportion of moisture contained.

One object of the invention, therefore, is to provide the discharge-opening with adjustable means for regulating the discharge from the revoluble drum.

The invention is shown in the accompanying drawings, in which—

Figure 1 is a vertical sectional elevation of the machine. Fig. 2 is a side elevation of the machine on the line 2 2 looking from the left toward the right. Fig. 3 is a vertical section 40 through the discharge-opening on the line 3 3. Fig. 4 shows a detail of ring-head.

Two vertical plates A B constitute opposite sides of the machine, and a close cylinder C is held and clamped securely between said plates by means of bolts d, extending from one plate to the other in a circle around the outside of the cylinder. A gasket e is confined at each end of the cylinder and between said ends and the vertical side plates, and this gasket makes a water-tight joint. A pipe f in

the bottom of the cylinder serves for draining off the water that accumulates. A revoluble shaft F has bearings g g' in the two vertical plates and carries a preferably tapered circular drum G, whose wall is composed of two shells or thicknesses h h' of woven wire, the inner one h being of closer mesh than the outer one h'. These two perforated shells are smaller at the entrance end than they are at the discharge end, and each end has a ring-head or wheel I I', whose hubs are secured fast to the shaft F. Each ring-head in the present instance has a rim which on the outside is V-shaped, and this rim takes into a circular groove i, formed on the inner surface 65 of each vertical plate. The two perforated or wire shells h h' have their ends secured to the ring-heads by a hoop at each end and rivets. A hoop j surrounds the end of the shell, and the end is bent back and over the outside 70 of the hoop, the bent part forming a sort of hook, and then the bent end and hoop are inserted into the ring-head I, and rivets k are passed through the bent part, also through the hoop j, and through the rim of the ring-head. 75

The vertical plate B has a circular neck l, which constitutes the opening, being of a size corresponding to the small end of the drum G, and a feeding-in hopper m connects with the said neck. The shaft-bearing g' is supported in the neck by a spider or stationary cross-arms n, one of which is shown in cross-section. Each cross-arm has a blade n' attached. The revoluble ring-head or wheel I also has cross-arms o, each of which carries a 85 blade o', which constitute rotary cutters. The direction of revolution of these ring-head cutters is such that their blades o' pass the stationary blades n' in manner to act like a shear and cut any material that may be passing 90 into the drum G. The inner side of each cross-arm o is beveled or oblique, as at p, (shown in the section in Fig. 1,) and the effect of this shape is that each of said cross-arms operates to draw into the drum the material that is being fed down the hopper m. This construction of the entrance to the perforated revoluble drum insures that the material from which water is to be separated, whatever it may be—scrap, animal matter, cooked fish, 100

or garbage—will be cut and also at the same time drawn into the centrifugal drum G.

The extremity of the shaft F within the circular entrance or neck l has an arm q fixed 5 on the shaft. This arm is revolved in the neck and acts on the material and serves as a stirrer-blade to loosen and agitate the material that is passing from the hopper through the neck, and thus prepares it for passing the 10 rotary cutters.

The ring-head or wheel I' at the large or discharge end has cross-arms r, which connect the V-shaped rim with the hub s, and said ring-head or wheel revolves with the shaft F. 15 These cross-arms r on the outer side are beveled or oblique, as at t, (shown in Fig. 1,) and the purpose of this form is to aid in the discharge of the material from the centrifugal drum through the opening u when the sliding door v in the vertical plate A is open or 20 partly open.

A shield or deflector w is bolted to the vertical plate A over the discharge-opening u, and said opening is controlled by the sliding door v, which latter is held in place by the deflector. One side w' of the deflector is free 25 from bolts to permit the door v to be opened by sliding sidewise. The sliding door v at one end carries an ear x with a screw-threaded 30 hole, and the threaded part of a screw x' passes through said hole. The ends of the screw which are not threaded have bearing 35 to revolve in the sides of the deflector, and said screw is provided with collars x² and x³, which take against the outer surfaces of said 40 sides and prevent the screw when it is turned from advancing. It is obvious that upon the revolution of the screw in the ear x the door v will travel or slide crosswise of the opening u.

A pulley y is mounted on the end of the shaft F, by which rotary motion is imparted to the drum G.

The operation of the device is as follows:

45 The wet matter to be treated is fed into the hopper m. The arm q, revolving with the shaft, loosens and agitates the material and prevents the circular entrance l from becoming clogged up and also tends to push the matter between 50 the stationary cross-arms n, having the cutter-blades n', toward the receiving end of the drum. The shaft F, ring-heads I I', carrying the cross-arms o and cutters o', and drum G at this time will be revolving at a high rate of 55 speed—say about from twelve to fifteen hundred revolutions per minute—the cutters o' passing the stationary blades n' in a manner to act as shears, and the material passing from the hopper into the drum will thereby 60 be cut into fine particles. The drum G at its small end receives the cut matter, and the centrifugal action due to the high revolution of the drum presses the material against the perforated walls h of the drum and the water separates from the material and passes 65 through the perforations into the cylinder C.

The drum G is tapered and is smallest at the receiving end and largest at the discharge end. Hence in the operation the material is gradually worked down the inclined walls of 70 the drum toward the discharge end and if the discharge-opening u is closed will bank up in the drum and become level with the receiving end. The sliding door v will be open more or less, according to the proportion of 75 water or moisture in the material that is being treated. If the material is very wet, the door will be set so as to leave but a small opening. If it is not so wet, a larger opening will be left. The smaller the opening the 80 longer time the material will be retained in the drum. When the material at the discharge end of the drum has been sufficiently freed from moisture, it will discharge through the opening u. As the cross-arms r on the 85 ring-head I are beveled, as at t, they will aid in discharging the material from the drum through the opening u. The operation is 90 continuous.

Having thus described my invention, what 90 I claim as new, and desire to secure by Letters Patent, is—

1. The combination of a perforated drum revoluble in a vertical plane; a feeding-in hopper opening into one end of the drum; a 95 stationary vertical plate closing the opposite end of the drum and said plate provided with an adjustable discharge-opening; and a close cylinder surrounding the drum to catch the 100 water thrown from the latter.

2. The combination of a perforated drum, revoluble in a vertical stationary plane; two vertical plates one at each end of the drum—one having a feed-in opening communicating with the small end of the drum and the other plate at the large end having a discharge-opening; and a sliding door that may be adjusted to increase or lessen the discharge-opening. 105

3. The combination of a perforated tapered drum, revoluble in a vertical plane; two vertical plates one at each end of the drum—one having a feed-in opening communicating with the small end of the drum, and the other plate at the large end having a discharge-opening; 115 stationary cross-arms in the feed-in opening each having a blade; cross-arms at the small or entrance end of the drum—each arm carrying a blade which coacts as a shear to cut the material entering the drum. 120

4. The combination of a shaft and perforated drum carried by the shaft; a feed-in neck communicating with the entrance end of the drum; stationary cross-arms in the feed-in neck; an arm fixed on the end of said 125 shaft on the entrance side of said stationary cross-arms and revoluble in the said feed-in neck.

5. A centrifugal machine operating continuously having in combination a perforated 130 tapered revoluble drum having an entrance end provided with cross-arms and blades—

the inner side of each cross-arm being bevelled or oblique to aid in drawing the material into the drum; a stationary vertical plate at the large end of the cylinder provided with a discharge-opening, and means at the discharge-opening to regulate and control the discharges from the drum.

In testimony whereof I affix my signature in the presence of two witnesses.
